UNITED STATES PATENT OFFICE.

BRUNO F. FREYMARK, OF ST. LOUIS, MISSOURI.

STAND-BOILER AND WATER-HEATER.

1,164,803.

Specification of Letters Patent. Patented Dec. 21, 1915.

Application filed July 8, 1914. Serial No. 849,712.

To all whom it may concern:

Be it known that I, BRUNO F. FREYMARK, a citizen of the United States, and a resident of the city of St. Louis and State of Missouri, have invented a new and useful Improvement in Stand-Boilers and Water-Heaters, of which the following is a specification.

This invention relates to combined water heaters and steam generators suitable for the use of bakers and others requiring steam intermittently.

The object of the invention is a steam generator which will furnish dry steam, which can be heated up with great rapidity, and which can be repaired with facility.

Other objects of the invention appear in connection with the description of the apparatus shown in the accompanying drawing, and what the invention consists in is more particularly defined in the appended claims.

In the drawing, in which the several parts of the device are respectively designated by reference numerals, Figure 1 is a vertical sectional view of the device, and Fig. 2 is a plan view of a heating coil.

Referring to Fig. 1, my improved boiler consists of a shell 11 in the form of a seamless steel tube or pipe arranged with its axis vertical and having screw threads cut on its ends. A cast-iron cap 12 is screwed on the upper end of the shell and a flange 13 is screwed on its lower end. A steel crown plate 14 is bolted to the flange 13, a suitable gasket being placed between the flange and the adjacent portion of the crown plate. The boiler shell is mounted on a stand comprising a cylindrical sheet-iron casing 15 supported on legs 16. The upper edge of the casing 15 is flanged outwardly and bolted to the flange 13 and crown plate 14. The lower end of the casing 15 is open, and a gas burner 17 having a pipe connection 18 with a gas main is arranged in the opening. The casing 15 has an opening in its side wall, which is closed by a door 19, to give access to the burner and to the interior of the casing. The casing 15 constitutes a combustion

chamber, and in order to provide means of escape for the burnt gases a flue 20 extends axially through the boiler, the lower end of the flue being expanded and beaded over into a hole in the middle of the crown plate 14, and the upper end of the flue extending through a stuffing box 21 at the mid-

dle of the cap 12. The stuffing box is provided with packing 22, and has a screw cap 23 and follower 24 for confining the packing around the flue 20 whereby a steam-tight joint is maintained. The flue can move lengthwise through the stuffing box without leaking steam or water, whereby it may expand and contract independently of the boiler shell.

Within the casing 15 is arranged a series of heating coils 25 one above another. The heating coils are separate from each other. Each coil consists of a continuous pipe wound in the form of a flat spiral. The ends of the pipe are turned up, and each end is provided with a union or coupling 26. The outer end of each spiral is connected to one of a number of nipples 28 screwed into tapped holes in the crown plate 14. The inner end of each spiral is led outside of the spiral and is connected to the projecting lower end of one of a number of circulation pipes 29 which are screwed through the crown plate 14 from inside of the boiler shell. The upper end of each circulation pipe 29 is curved around a half circle, forming a hook-shaped extremity 30 which directs downward the steam or water issuing therefrom.

The boiler is provided with a feed water inlet pipe 31, a glass water gage 32, a steam or water pressure gage 33, a spring safety valve 34, and hot water and steam pipes 35, 36, all of usual construction. The boiler also has an air valve 37, which permits the passage of air from and into the boiler at the start and close of the steam generating process. The air valve 37 is of usual construction, and prevents the passage of water or steam through it when the pressure in the boiler is greater than the minimum pressure for which the air valve is set. The air valve expedites the generation of steam at the start of the process and prevents overheating the coils 25.

The operation of the device is extremely simple. If hot water is desired, the valve in the water supply pipe 31 is opened and left open, so that the boiler becomes filled with water at the pressure of the water supply. The gas is turned on and the burner lighted, whereupon the water in the coils is heated, and turned partly into steam. The steam passes through the ends of the coils, part going through the nipples 28 directly into the lower part of the boiler where it is con-

densed, and part going through the pipes 29 into the upper part of the boiler. The steam going through the pipes 29 warms the water therein and tends to carry it along into the top of the boiler, thereby preventing it from returning to the coils. Water flows through the nipples 28 into the coils to replace that evaporated and discharged through the pipes 29, thus setting up rapid circulation through the coils, and keeping them from getting overheated.

When steam is desired, the valve in the supply pipe 31 is closed and the water is drawn off through the plug 38, or other suitable means, until the boiler is about one-third full. The upper part of the boiler will be automatically filled with air as the water level falls. The gas is turned on and the burner is lighted, thereby heating the coils and turning the water therein into steam. The air valve keeps the pressure low, prevents violent fluctuations of pressure, and enables and promotes circulation of the water through the coils. The steam is generated in the coils intermittently. First it blows through the water in the nipples 28 and in the pipes 29 and out through their top ends, and forces air out of the boiler through the air valve. The steam condenses in the cool boiler and as it condenses a vacuum is produced in the boiler, and the hot steam in the coils expands and continues to flow out of the coils until air rushing into the boiler through the air valve equalizes the pressure in the coils and in the boiler and forces water through the nipples 28 into the coils. Thereupon a quantity of steam is formed as before, and the cycle of operations is repeated. After a number of repetitions of the cycle of operations the water in the boiler and in the pipes 29 will be heated to such an extent that it will not condense the steam, and the water in the pipes 29 will be gradually blown out of the upper ends of the pipes. When there is no longer any hydrostatic pressure on the ends of the coils attached to the pipes, water will flow continuously into the coils through the nipples 28, and rapid continuous generation of steam in the coils will ensue. The steam pressure has no effect on the circulation of water through the coils after it is established because it is the same at both ends of each coil. The hydrostatic head on the intake ends of the coils is not great enough to flood the long flat coils with water faster than it is turned into steam. Hence, the steam issuing from the coils will be superheated more or less, depending upon how hot the gas flame is regulated to burn. The lower coils, which are the nearest the flame, have a greater hydrostatic head upon them, and consequently more water flowing through them, than the upper coils; and the size of the pipe, length of the coil, and size of the

burner are so chosen that the coils all keep at about the same temperature, whereby uneven heating and uneven deterioration of the coils is overcome. Moreover, the construction and arrangement of the coils is such that one or more may be readily replaced when burnt out without returning the boiler to the shop. Likewise, the crown plate 14 and flue 20 may be removed and replaced as a unit, together with all the coils, without returning the boiler to the shop, and without requiring special tools or workmen for the operation.

It is evident that modification in the forms and arrangement of the parts of the device may be made without departing from the invention; and the invention is not restricted to the precise forms and arrangement shown.

What I claim is:

1. A boiler consisting of a seamless pipe having a cap screwed on one end and a flange screwed on its other end, a flat crown plate detachably secured to said flange, heating coils detachably secured to the under side of said crown plate, and a combustion chamber detachably secured to the under side of said crown plate, said combustion chamber being clear of said heating coils and mounted on legs for supporting said boiler.

2. A boiler consisting of a seamless pipe having a cap screwed on one end and a flange screwed on its other end, a flat circular crown plate detachably secured to said flange, a central flue secured to the middle of said crown plate at one end and with its other end extending through said cap and slidably arranged with respect thereto, heating coils detachably secured to the under side of said crown plate, and a combustion chamber detachably secured to the under side of said crown plate, said combustion chamber being mounted on legs for supporting said boiler.

3. A boiler consisting of a seamless pipe having a cap screwed on one end and a flange screwed on its other end, a flat crown plate detachably secured to said flange and carrying a central flue, a detachable connection between said flue and said cap, a plurality of heating coils with their ends detachably secured to the under side of said crown plate, and a combustion chamber surrounding said coils and detachably secured to said crown plate, said combustion chamber being mounted on legs for supporting said boiler.

4. A combined hot water heater and boiler having an upright shell of considerable height in proportion to its diameter, a flat heating coil horizontally arranged below said shell, one end of said heating coil having a pipe connection with the lower portion of said shell and the other end of said coil being connected to a pipe which opens

into the upper portion of said shell, a water inlet valve, a water outlet from the lower portion of said shell, and an air valve connected to the upper portion of said boiler.

- 5 5. A combined hot water heater and boiler having an upright shell of considerable height in proportion to its diameter, a plurality of flat heating coils horizontally arranged one over the other below said shell, 10 one end of each of said heating coils having a pipe connection with the lower portion of said shell and the other end of each of said coils being connected to a pipe which opens into the upper portion of said shell, a water inlet valve, a water outlet from the lower portion of said shell, and an air valve connected to the upper portion of said boiler.
- 15 6. An upright boiler having a crown sheet and a heating coil arranged below said crown sheet, said heating coil having one end connected to said crown sheet and the other end

connected to a pipe which opens into the upper portion of said boiler, and a relief valve connected to the upper portion of said boiler and arranged to permit air to flow into and 25 out of said boiler.

7. An upright boiler having a crown sheet and a plurality of heating coils arranged one over the other below said crown sheet, each one of said heating coils having one end 30 connected to said crown sheet and the other end connected to a pipe which opens into the upper portion of said boiler, and a relief valve connected to the upper portion of 35 said boiler and arranged to permit air to flow into and out of said boiler.

Signed at St. Louis, Missouri, this 6th day of July, 1914.

BRUNO F. FREYMARK.
